UNITED STATES PATENT OFFICE.

RAYMOND E. S. COX, OF DENNISON, OHIO.

WIRE-STRETCHER.

1,102,144.

Specification of Letters Patent. Patented June 30, 1914.

Application filed December 2, 1913. Serial No. 804,238.

To all whom it may concern:

Be it known that I, RAYMOND E. S. Cox, a citizen of the United States, residing at Dennison, in the county of Tuscarawas and 5 State of Ohio, have invented new and useful Improvements in Wire-Stretchers, of which the following is a specification.

This invention relates to wire stretchers and it consists in the novel features here-
10 in after described and claimed.

An object of the invention is to provide a wire stretcher of simple structure which is positive in its action in gripping the wire and a stretcher which may be readily trans-
15 formed into an implement for digging holes in the ground and may also be used for tamping earth about posts set in the said holes.

With the above object in view the device
20 comprises a staff provided at one end with a flattened head and at its opposite end with a socket. If desired the said staff may be hollow throughout its length. A detachable head is adapted to be connected with the
25 staff at the socket end thereof the said head having a screw threaded shank adapted to engage the said socket. The detachable head is made in the form of a claw which may be used for drawing nails or spikes
30 from timbers. A wire securing device is adapted to be connected with the said head and when in position may retain a strand of wire so that the said wire can be stretched when the staff is used as a lever.

35 In the accompanying drawing:—Figure 1 is a perspective view of the wire stretcher. Fig. 2 is a detailed sectional view of parts of the same. Fig. 3 is a transverse sectional view of the head of the stretcher.

40 The wire stretcher includes a handle staff 1 which is provided at one end with a fixed flattened head 2 which may be used for tamping the earth about a post which is positioned in a post hole. The staff 1 is pro-
45 vided at that end opposite the end at which the head 2 is located with a socket 3. The said socket is internally threaded and may be of any desired length or in fact the staff 1 may be hollow throughout its length.

50 A detachable head 4 is provided with a threaded shank 5 which is adapted to be screw threaded into engagement with the socket 3. The head 4 is further provided with claw extremities 6 of usual configura-
55 tion. This head when applied to the staff

may be used for the purpose of withdrawing nails or spikes from timbers or other material. Posts or blocks 7 are detachably connected with the head 4 and are preferably nested in the concaved sides of the claws 6. 60 Screws 8 or other suitable securing device may be employed for holding the posts in position upon the claws of the head. A block 9 is adapted to be positioned against the side edges of the post 7 and the said 65 block is provided with a recess 10 which registers with the opening between the claws 6 of the head 4.

A roller 11 is journaled in the head 4 and one part of its peripheral por- 70 tion enters the recess 10. The said roller 11 is provided with an eccentrically disposed periphery and the roller is further provided with a handle 12. It is obvious that by using the handle 12 the roller 11 may be 75 turned so that the shallow part of its peripheral portion is disposed in the recess 11. When this is done a wire may be inserted between the periphery of the roller and the side wall of the recess and said wire may be 80 continued through the opening between the claws 6. Then by using the handle 12 the roller 11 may be turned so that the deep part of its peripheral portion may engage the said wire and bind the same against the 85 side of the recess 10. Then by placing the extremities of the claws 6 against a post or other fixed object the staff 1 may be used as a lever and the wire which is gripped between the roller and the side of the recess 90 10 may be stretched.

Having described the invention what is claimed is:—

1. A stretcher comprising a staff provided at its end with a socket, a head having a 95 threaded shank adapted to engage the socket said head being provided with spaced claws which are curved longitudinally, posts detachably connected with the claws, a block positioned against the claws and the said 100 posts and having a recess which registers with the opening between the claws, a roller having an eccentric periphery journaled in the block with the peripheral portion of the roller entering the recess and means for 105 turning the roller.

2. A stretcher comprising a staff provided at one end with a threaded socket and at its opposite end with a flat tamping head, a 110 claw head provided with a threaded shank

adapted to engage the socket, the claws of said head being spaced from each other and curved longitudinally, posts detachably connected with the claws of said head, a block 5 mounted against the claws and the posts and having a recess which registers with the opening between the claws, an eccentric roller journaled in the head and having its peripheral portion projecting into the recess

said roller being provided with a handle 10 which projects beyond its periphery.

In testimony whereof I affix my signature in presence of two witnesses.

RAYMOND E. S. COX.
